US00D840358S

(12) **United States Design Patent** (10) Patent No.: **US D840,358 S**
Zhao et al. (45) Date of Patent: **** Feb. 12, 2019**

(54) **CONTROL DEVICE**

(71) Applicant: **QINGDAO BRIGHT MEDICAL MANUFACTURING CO., LTD.**,
 Qingdao, Shandong Province (CN)

(72) Inventors: **Dezheng Zhao**, Qingdao (CN);
Mengtian Yi, Qingdao (CN)

(73) Assignee: **QINGDAO BRIGHT MEDICAL MANUFACTURING CO., LTD.**,
 Qingdao (CN)

(**) Term: **15 Years**

(21) Appl. No.: **29/595,916**

(22) Filed: **Mar. 3, 2017**

(30) **Foreign Application Priority Data**

Nov. 10, 2016 (CN) 2016 3 0546026

(51) LOC (11) Cl. **13-03**

(52) U.S. Cl.

USPC **D13/168**; D24/186

(58) **Field of Classification Search**

USPC D13/168, 171; D24/133, 186, 187

(57) **CLAIM**

The ornamental design for the control device, as shown and described.

DESCRIPTION

FIG. 1 is a front View of a first embodiment of the control device;

FIG. 2 is a rear side View thereof;

FIG. 3 is a left side View thereof;

FIG. 4 is a right side View thereof;

FIG. 5 is a bottom View thereof; and

FIG. 6 is a top View thereof.

FIG. 7 is a front View of a second embodiment of the control device;

FIG. 8 is a rear side View thereof;

FIG. 9 is a left side View thereof;

FIG. 10 is a right side View thereof;

FIG. 11 is a bottom View thereof; and,

FIG. 12 is a top View thereof.

The broken lines are for illustrative purposes only and form no part of the claimed design.

1 Claim, 6 Drawing Sheets
